UNITED STATES PATENT OFFICE.

MAXIMILLIAN G. VOIGTLANDER, OF HARRISON, OHIO, ASSIGNOR OF ONE-HALF TO JAMES A. GRAFT, OF HARRISON, OHIO.

SIGNAL SYSTEM FOR RAILWAYS.

No. 884,784.

Specification of Letters Patent.

Patented April 14, 1908.

Application filed August 9, 1906. Serial No. 329,828.

To all whom it may concern:

Be it known that I, MAXIMILLIAN G. VOIGTLANDER, a citizen of the United States, residing at Harrison, in the county of Hamilton and State of Ohio, have invented certain new and useful Improvements in Signal Systems for Railways, (Case C,) of which the following is a specification.

My present invention relates to a signal system for railways and is adapted for employment in connection with the signal system for railways shown, described and claimed in my application for Letters Patent of the United States, Serial No. 232,678, filed 15 November 14, 1904, and in my applications of even date herewith designated respectively as Cases A and B; and being respectively Serial Nos. 329,826 and 329,827, and I have herein shown and described some of the 20 features and combinations of elements shown described and claimed in said respective applications for Letters Patent, to which reference is respectfully made.

The present invention will be readily understood from the following description and claims, and from the drawings, in which latter:

Figure 1 represents a plan view showing a railway track arranged into electrical blocks and provided with tracks or local contacts, the electrical connections being diagrammatically shown. Fig. 2 is a diagrammatic representation of the signaling recording and controlling apparatus on the vehicle, 35 with their electrical connections. Fig. 3 is a side elevation of the electric traveling and local contacts. Fig. 4 is a front elevation of the recording apparatus. Fig. 5 is a side elevation of the same, partly in vertical section 40 on the line $x-x$ of Fig. 4, and partly with the casing removed to show interior construction. Fig. 6 is a front elevation of the control. Fig. 7 is a central vertical section of the same on the line $y-y$ of Fig. 6. Fig. 8 is 45 a vertical cross-section of the same on the line $z-z$ of Fig. 7. Fig. 9 is a side elevation of one of the control-levers; and, Fig. 10 is an end elevation of the same shown in connection with its terminals.

50 A represents the track which I have shown in its simplest form as a single track, although it is obvious that my invention is applicable to double tracks and sidings, switches, cross-overs and other tracks of more complicated 55 arrangement, as more fully indicated in said

other applications. The track comprises a continuous rail 1 and a mating rail therefor which is divided into sections or blocks 2 separated by insulations 3 for forming succeeding blocks in the track represented at B, 60 C and D. Each of the blocks has local or track contacts electrically connected therewith, which are projected into preceding blocks, and I have shown these contacts as comprising a home plate and a distant plate. 65 The home plates are indicated at 4 and the distant plates at 5, the distant plate being preferably located adjacent the distant post represented at 6. The home-plate is electrically connected with its block by an electric conductor 7 while the distant plate is connected with its block by an electric conductor 8 which is shown as connecting with the conductor 7, although it may be connected with the home plate. Vehicles are 70 adapted to travel upon the track, the vehicles being provided with signals, registers and controls which have electric connection with each other and are adapted to make electric connection with the track and local 75 contacts in manner which will now be described. The local contacts may consist of a plate having upturned ends 11 and secured to brackets 12 attached to but insulated from the tracks by an insulated connection 13. 85

The vehicle is provided with traveling contacts adapted to make electric contact with the local contacts and are so arranged that the electric contact may be made whether the vehicle be proceeding forward or 90 backward, and for this purpose I provide such traveling contact at each side of the vehicle. Thus at the right side of the vehicle, looking in the direction of its forward travel, I provide a traveling contact 95 14, and at the left side of the vehicle, I provide a traveling contact 114. These traveling contacts may be in the form of brushes, rolls or shoes adapted to take under the local contacts and are preferably arranged for 100 pressing yieldingly upward. I have shown the traveling contacts mounted at the outer ends of spring-arms 15 having an outwardly projected portion 16 for forming sidewise clearance, the spring-arm being secured to 105 but insulated from the truck 17 of the vehicle by an insulated connection 18. A depending post 19 may limit the upward movement of the spring-arm and prevent excessive vibration thereof.

Upon the vehicle there is located a pair of signals 20 120 shown as electric bells, a pair of energizers 21 121 shown as batteries, a register 22 and a controlling device 23.

5 The register may be of any desirable form and comprise a case 25 in which there is a clock mechanism 26 and a dial-plate 27 operated thereby, the dial-plate being adapted to have attached thereto suitable dials 28 10 on which are depicted the time or hours of the day as shown at 29, the time divisions being of as short duration as may be desired, the clock mechanism being arranged to advance the dial corresponding to the time, so 15 that the time indicated on the dial may at the proper moment and in correct sequence be opposite the pointer. Thus the hour-hand shaft 30 of the clock mechanism may be connected with the dial-plate shaft 31 by 20 a series of gears 32 33 34 and 35 to cause the dial-plate to rotate half as fast as the hour-hand shaft, imparting a complete rotation to the dial-plate once in twenty-four hours. Positioning pins 36 may be provided for positioning the dial correctly with 25 relation to the pointer on the dial-plate to correspond with the time indicated by the clock mechanism. A door 37 provided with a lock 38 may be provided for the case, so 30 that the dials may be inserted and removed only by an inspector or other officer provided with its key. The pointer 39 is provided with a marking point 40 arranged to contact with the dial for leaving a mark 35 thereon. The pointer is actuated by an electro-magnet 41 or other suitable actuating device which is adapted to actuate the pointer. The pointer is secured to an armature 42 arranged to be attracted by coils 43, 40 but normally held in retracted position by a spring 44 against a stop 45.

The signal and recorder are adapted to be actuated on contact of the traveling contact with a local contact and the occupancy or 45 derangement of the block with which said local contact is in electric connection as more fully explained in my aforesaid applications. In the form shown, I have shown the signal as a separate device, although it 50 is obvious that the signal and recorder may be parts of the same structure. The signals, register and control, in a locomotive, will be at the engineer's position, and in an electric vehicle at the motorman's or other 55 operator's position.

I have provided a control whereby either of the signals and the register may be connected with either of the traveling contacts on the vehicle for the purpose of connecting 60 said register and signals with the right hand traveling contact when the vehicle is proceeding in a forward direction or with the left hand contact when the vehicle is proceeding in a backward direction, the said control 65 also having means whereby the register may

be short-circuited on the vehicle with either signal for testing said signals and enabling the one of greater efficiency to be connected with the traveling contact it is desired to employ.

23 is a control comprising three switches F G H, the switch F comprising terminals 51 52 and 53, the switch G comprising terminals 61 62 and 63, and the switch H comprising terminals 71 72 and 73, these switches 70 respectively having connecting plates or bridges 54 64 74 for electrically connecting the intermediate with either of the end terminals of said switches. The control preferably comprises a case 80 to which the respective terminals are secured by insulated connections, the terminals comprising binding posts located outside the case, with which binding posts the respective electric conductors for said contacts or terminals are 80 connected. The bridge-pieces are respectively secured to but insulated from arms 55 65 75 respectively secured to an inner shaft 56, an intermediate sleeve 66 and an outer sleeve 76, outer arms 57 67 77 being respectively secured to said shaft and sleeves for manipulating the bridges. The shaft and sleeves rock within one another, the outer sleeve rocking in the lid 81 of the case, having a collar 82 secured thereto for positioning the same in the lid. The lid is preferably removable and is provided with indexes 58 68 and 78 for the respective switches. The terminals inside the case are preferably provided with a depression 83, as shown in Fig. 10, the bridge being a spring-plate having curved ends 84 for being received by the depressions for positioning the same and making electric contact therewith, the bridge being insulated from the arm to which it is secured by insulation 85.

An electric conductor 86 connects the intermediate terminal 71 of switch H with the terminal 87 of the register. An electric conductor 88 connects the terminal 72 of switch H with the traveling contact 14. An electric conductor 89 connects the terminal 90 of the register with the intermediate terminal 51 of switch F. An electric conductor 91 connects the terminal 52 of switch F with the binding post 92 of bell 20. An electric conductor 93 connects the binding post 94 of bell 20 with the terminal 95 of battery 21. An electric conductor 96 connects the terminal 97 of battery 21 with the terminal 98 of the battery 121. An electric conductor 99 connects the terminal 100 of battery 121 with the binding post 101 of bell 120. An electric conductor 102 connects the binding post 103 of bell 120 with the terminal 53 of switch F. An electric conductor 104 connects the electric conductor 96 with the axle and wheels E of the vehicle. An electric conductor 105 connects one of the end terminals 73 of switch H with the traveling contact 114. 130

An electric conductor 106 connects the conductor 104 with the intermediate terminal 61 of switch G. An electric conductor 107 connects one of the end terminals 62 of switch G with the conductor 105, and an electric conductor 108 connects the other end terminal 63 of switch G with the conductor 88.

The switch F may be termed the signal switch, the switch H the traveling contact switch, and the switch G the short circuiting switch, and with these switches either signal may be brought in circuit with either traveling contact through the register, and the electric connections of either traveling contact with both signals and the register may be short circuited for purposes of testing. The traveling contacts are adapted to make contact with the local contacts, electric connection being thereby formed between the local contact through the traveling contact, the selected bell and battery, the register, to the axle and wheels of the vehicle, thus completing the circuit with the exception of the spanning of the rails of the track.

If now a vehicle be present in the block in advance, with which the local contact has connection, a complete circuit will be formed and the bell will ring and the register operate, or if any other derangement be caused in the block in advance, such as mentioned for instance in the aforementioned applications for patents; the said register will indicate such derangement and the signal operate for calling attention to the same. The pointer or marker of the register is adapted to normally point or mark along a predetermined line of the dial, as see the marking 109 in Fig. 2, the dial being moved by the clock mechanism corresponding in time to the time markings on the dial. As soon as electric energy passes through the register and bell, that is, as soon as any vehicle is present in said block in advance or any derangement takes place for sounding the signal, electric energy will pass through the coils 43 to attract the armature 42 for moving the pointer or marker of the register and causing the marking or pointing to take place in an abnormal position, as see the abnormal marking 110, which is indicated on the dial, the indications in abnormal position on the dial continuing during obstruction or derangement of the track as stated. As soon as the obstruction or derangement is removed, the marker or dial will return to normal position, the moment of time of such return being indicated on the dial, so that a permanent record may be had of the time when such obstruction or derangement took place, how long it continued, and when it ceased.

Having thus fully described my invention what I claim as new and desire to secure by Letters-Patent is:

1. In a signal system for railways, the combination of a track comprising an electrically

continuous rail and a mating rail divided into blocks, local contacts at both sides of said track, a vehicle, traveling contacts thereon arranged to make contact with said local contacts, a plurality of traveling signals, a recorder, said plurality of signals and recorder having electric connection with said traveling contacts and an axle and wheels of said vehicle, and an electric switch in said connection for operatively electrically connecting either of said signals with said recorder. 70 75

2. In a signal system for railways, the combination of a track comprising an electrically continuous rail and a mating rail insulated into blocks, local contacts at both sides of said track, a vehicle, traveling contacts on said vehicle for said local contacts, a traveling signal and traveling recorder on said vehicle having electric connection with either of said traveling contacts, and an electric switch on said vehicle for operatively electrically connecting said signal and recorder with either of said traveling contacts. 80 85

3. In a signal system for railways, the combination of a track insulated into blocks, local contacts at either side thereof, a vehicle therefor, contacts thereon for said local contacts, a plurality of traveling signals and a traveling recorder on said vehicle, said respective signals having electric connection with said recorder comprising an electric switch for operatively electrically connecting either of said signals with said recorder, said signals having electric connection with said traveling contacts comprising an electric switch operatively electrically connecting either of said traveling contacts with either of said signals, substantially as described. 90 95 100

4. In a signal system for railways, the combination of a track insulated into blocks, local contacts at either side thereof, a vehicle therefor, contacts thereon for said local contacts, a plurality of traveling signals and a traveling recorder on said vehicle, said respective signals having electric connection with said recorder comprising an electric switch for operatively electrically connecting either of said signals with said recorder, said signals having electric connection with said traveling contacts comprising an electric switch operatively electrically connecting either of said traveling contacts with said signals, a source of electric energy, short-circuiting connections on said vehicle from said source to said signals and recorder, and a switch in said short-circuiting connections through either of said signals and said recorder. 110 115 120

5. In a signal system for railways, the combination of a track divided into blocks, a vehicle, local contacts for forward travel and local contacts for rearward travel of said vehicle electrically connected with said blocks, a traveling contact on said vehicle for forward travel and a traveling contact on said vehicle for rearward travel of said vehicle. 125 130

cle respectively arranged for making contact with said respective local contacts, a plurality of signals and recorder on said vehicle having electric connections with said respective traveling contacts and an axle and wheels of said vehicle, and a plurality of electric switches in said last-named electric connections for electrically connecting either of said traveling contacts with either of said signals and recorder, substantially as described.

6. In a signal system for railways, the combination of a track divided into blocks, a vehicle, local contacts for forward travel and 15 local contacts for rearward travel of said vehicle, electrically connected with said blocks, traveling contacts on said vehicle respectively for forward and for rearward travel of

said vehicle, a plurality of signals and a recorder on said vehicle; electrical connections 20 on said vehicle for said signals, traveling contacts and an axle and wheels of said vehicle; electric switches in said last-named electric connections for electrically connecting either of said traveling contacts with either of said signals and recorder, and a switch in said last-named electric connections for short-circuiting said recorder with either of said signals on said vehicle, substantially as described.

In testimony whereof, I have subscribed 30 my name hereto in the presence of two subscribing witnesses.

MAXIMILLIAN G. VOIGTLANDER.
